(57) **CLAIM**

The ornamental design for a contour truck rack, as shown and described.

DESCRIPTION

FIG. 1 is a perspective view of the contour truck rack showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view showing the contour truck rack on a truck.
In the drawings, the broken lines in FIG. 8 depict a truck and no part of the claimed design.
